(57) **CLAIM**

The ornamental design for a folding bike frame, as shown and described.

DESCRIPTION

FIG. 1 is a perspective view of a folding bike frame, showing my new design;

FIG. 2 is a bottom perspective view thereof;

FIG. 3 is a right side view thereof;

FIG. 4 is a front view thereof;

FIG. 5 is a back side view thereof;

FIG. 6 is a left side view thereof;

FIG. 7 is a top view thereof;

FIG. 8 is a bottom view thereof; and,

FIG. 9 is a perspective view thereof shown in an alternative configuration.

The broken lines are included for the purpose of illustrating the environmental structure and form no part of the claimed design.
